UNITED STATES PATENT OFFICE.

THOMAS STEBNER, OF MANDAN, NORTH DAKOTA.

LOCK.

1,365,861.

Specification of Letters Patent. Patented Jan. 18, 1921.

Application filed July 21, 1919. Serial No. 312,257.

To all whom it may concern:

Be it known that I, THOMAS STEBNER, a citizen of the United States, residing at Mandan, in the county of Morton and State of North Dakota, have invented certain new and useful Improvements in Locks, of which the following is a specification.

This invention relates to locks, and an object of the invention is to provide a lock, which will require a plurality of keys, movable through predetermined arcs and at predetermined times for either locking or unlocking the lock structure, thereby providing a lock particularly adapted for use upon safe deposit vaults, safes or other devices, where it is desirable to have the said device opened only in the presence of two or three persons.

Another object of the invention is to provide a lock structure in which the slidable bolt, is restrained from movement by a plurality of spring operated tumblers adapted to be operated by keys for permitting slidable movement of the locking bolt, which bolt is moved longitudinally by certain of the keys after they have operated the tumblers and also to provide an auxiliary locking lug, carried by a flat spring and engaging in a recess in the slidable locking bolt, which tumbler must be moved out of the recess, by an outward movement of one of the keys during operation of the lock to permit the movement of the locking bolt, and further to provide a plurality of tumbler receiving notches in the sliding bolt, for each tumbler, which will require successive operations of the tumblers, in either locking or unlocking the lock structure.

Other objects of the invention will appear in the following detailed description taken in connection with the accompanying drawings, forming a part of this specification, and in which drawings:

Figure 1 is a section through the housing of the lock structure illustrating the locking bolt in an unlocked position, and showing certain of the respective keys in position with respect to their tumblers.

Fig. 2 is a view similar to Fig. 1 illustrating the locking bolt in a locking or extended position, and showing the keys in place therewith.

Fig. 3 is a cross section taken on the line 3-3 of Fig. 2.

Fig. 4 is a cross section on the line 4-4 of Fig. 1.

Fig. 5 is a fragmentary cross section on the line 5-5 of Fig. 2.

Figs. 6, 7 and 8 are side elevations of the bit portions of the keys showing companion portions of the housing of the lock structure in sections.

Referring more particularly to the drawings, wherein like characters indicate like and corresponding parts throughout the several views, 10 and 11 indicate the supporting plates of the lock structure between which the locking bolt 12 is slidably mounted. The longitudinal movement of the locking bolt structure 12 is guided by suitable guides 13 and this locking bolt has a reduced portion 14 on one end, which is adapted for projection into the keeper when the lock structure is in a locked position.

The main body 15 of the locking bolt structure 12 is provided with a plurality of spaced notches 16 in one side thereof, which are adapted to receive therein the angular portion 17 of a pivotally mounted tumbler 18. The tumbler 18 is provided with a substantially hook shaped extension 19, which projects beneath the body 15 of the locking bolt 12, extending beyond the edge of the body opposite to that upon which the tumbler is pivoted and in the path of the bit 20 of the key 21. The stem of the key is hollow, or provided with an axial recess for fitting over the key-post 22. A spring 23 engages the tumbler 18 and urges the tumbler toward the body 15 for urging the portion 17 thereof in one of the notches 16, to lock the body 15 and consequently the entire bolt structure 12 against sliding movement. The usual obstruction 24 is provided to prevent the operation of these tumblers 18 by any key except the key 21. The edge of the body 15, alongside of which the key 21 is mounted is provided with cut-out portions 25 forming shoulders 26, against which the bit of the key is adapted to engage to longitudinally shift the locking bolt 12.

A second tumbler 27 is pivotally mounted upon a suitable pin 28 upon the opposite side of the body 15 from the tumbler 18 and this tumbler 27 is also provided with the lateral shoulder or portion 29 adapted to engage in any one of a plurality of notches 30 formed in the edge of the body 15 opposite to the edge in which the notches 16 are formed. The tumbler 27 has an arcuate portion 30 which extends over the body 15 of the lock-

ing bolt 12 and presents a convexed surface for engagement by the bit 31 of the key 32 which key like the key 21 has a recess in its stem for engagement over a key post 33 carried by the plate 11. The bit 31 of the key 32 is shaped to pass over an obstruction 34 to permit rotary movement of the key to operate its part of the lock structure. A spring 35 engages the tumbler 27, and urges the angled shoulder 29 thereof toward the adjacent edge of the body 15.

The edge of the body 15 adjacent that which the key 32 is mounted is provided with cut-out portions 36 forming abutments 15 against which the bit 31 of the key 32 is adapted to engage for longitudinally moving the locking bolt structure 12 by rotary movement of the key 32.

Positioned at the side of the body 15 of the locking bolt 12 upon which the tumbler 18 is mounted and near the end of the locking bolt body opposite that near which the tumbler 18 is mounted is pivotally mounted a substantially U-shaped tumbler 37 provided with a lateral enlargement 38 for engagement in any one of the notches 39 formed in the adjacent edge of the body plate. The inner side or leg 40 of the U-shaped tumbler 37 is positioned beneath the body 15, and in the path of the bit 41 of the key 42. This key 42 is adapted to be rotatably mounted upon a key post 43 and a suitable lug or obstruction 44 is provided, being formed upon the plate 11 to prevent operation of the tumbler 11 by a key of any construction except that of the key 42. This post 43 and lug 44 are positioned beneath the body plate 15 and the latter is provided with a longitudinally extending cut out portion 45 to permit the insertion of the key 42 through the body plate for operating the tumbler 37 to move the lateral extension 38 out of either of the notches 39. A flat spring 46 engages the outer side 45 of the tumbler 37 for urging the lateral extension 38 into one of the notches 39.

The body 15 is provided with a longitudinal slot 47 through which a pin 48 extends, the said pin and slot forming means for guiding the longitudinal movement of the locking bolt structure 12.

The body is provided with a recess 49 in its outer face in which a lug 50 is urged by means of a flat spring 51. The flat spring 51 is carried by the plate 10 and has a laterally extending lug 52 formed thereon, and positioned to be engaged by the outer edge of the bit 20 of the key 21 so that when the key is drawn outwardly it will spring the lug 50 out of the recess 49 permitting longitudinal movement of the locking bolt 12 under action of the respective keys. To lock the lock structure, the operation is as follows: Insert keys 32, 42, and 21 upon the key posts 33, 43, and 22, re-

spectively. Turn or rotate the key 32 one half turn to the left and key 21 one half turn to the right. This rotation of the key 32 pushes back the tumbler 27 and the rotation of the key 21 pushes back the tumbler 18, releasing the locking bolt 12 at 16 and 30 respectively. Rotate or turn the key 32 about one-eighth of a turn farther to the left and the key 21 approximately one-eighth of a turn farther to the right, which causes the key 32 to push against the locking bolt at the outermost shoulder 36, and the key 21 to push against the outer shoulder 26 pushing the locking bolt forward until it is locked by the tumbler 37 and so the outermost notch 39 and by the lug 50 which drops into the recess 49. The key 42 is then rotated one quarter of a turn to the right and pushes back the tumbler 37 releasing the movable locking bolt 39. Rotate the key 21 to the right and at the same time pulling it toward the top plate 10 to draw the lug 50 out of the recess 49. The key 21 then pushes the locking bolt forward by engagement against the outer shoulder 26 pushing it forward until it locks at the second recess 16 by means of the tumbler 18 and at the second recess 30 by means of the tumbler 27. Turn or rotate keys 32 and 21 as before and they release removable locking bolt 12 at 16 and 30 and push or exert pressure against the second shoulder 26 and second shoulder 36, pushing the locking bolt forward until it locks at 55 by the insertion of the lugs 50 into this recess 55, which is positioned inwardly of and in alignment with the recess 49 and also by the tumbler 37 at the innermost recess 39. Turn key 42 to the right and release the locking bolt at the innermost recess 39 and turn the key 21 to the right, pulling it toward the top plate 10 to lift the lug 50 out of the recess 55. Turn key 32 to the left at which time the key 32 pushes the locking bolt structure 12 at the inner shoulder 36 and the key 21 pushes against the innermost shoulder 26, forcing the locking bolt 12 forwardly until it locks at the third recess 16 by the tumbler 18 and at the innermost recess 30 by the tumbler 27. Turn the keys in the same direction that each has been previously turned and withdraw them from the lock. This completes the locking operation.

The unlocking operation of the lock structure is as follows: Insert all three of the keys at their proper places and turn the key 32 to the right and the key 21 to the left which releases the locking bolt at the third recess 16 and innermost recess 30 and pushes the locking bolt inwardly until it is locked at the innermost recess 39 and at the recess 55. Turn key 42 to the right to release the locking bolt at the innermost recess 39. Turn keys 32 and 21 to the right and left respec-

tively, pulling key 21 toward the top plate 10 to release the lug 50 from the recess 55, and push the bolts inwardly until it is locked at the third recess 30 by the tumbler 27 and at the second recess 16 by the tumbler 18. Then turn the key 32 to the right releasing the locking bolt at the third recess 30 and turn the key 21 to the left releasing the locking bolt at the second recess 16 and then 10 pushing the locking bolt inwardly until it is locked at the outermost or first recess 39 by the tumbler 37 and at the recess 49 by the lug 50. Turn the key 42 to the right to release the locking bolt at the outermost recess 39 and turn the key 32 to the right and the key 21 to the left, forcing the locking bolt inwardly until it locks at the outermost recess 30 by the tumbler 27 and at the outermost or first recess 16 by the tumbler 18. 20 Complete the turn of each key and withdraw all of the keys which completes the operation of unlocking the lock.

Changes in details may be made without departing from the spirit of this invention, 25 but;

I claim:

1. In a lock, the combination of a locking bolt provided with a plurality of recesses therein, tumblers for locking engagement in 30 said recesses, keys for operating said tumblers, one of said tumblers normally lying out of locking engagement with the locking bolt while the remainder are in locking engagement with their respective recesses.

35 2. In a lock, the combination of a locking bolt provided with a plurality of recesses in the side edges thereof, tumblers for locking engagement in said recesses, keys for rocking said tumblers, one of said tumblers normally lying out of locking engagement with the locking bolt while the remainder are in locking engagement with their respective recesses, said second named tumbler adapted to move into locking engagement 40 with its recess when the other tumblers are moved out of locking positions and the bolt is slightly advanced.

3. In a lock, the combination of a locking bolt provided with a plurality of recesses 50 in the side edges thereof, tumblers for locking engagement in said recesses, keys for rocking said tumblers, one of said tumblers normally lying out of locking engagement with the locking bolt while the remainder are in locking engagement with their respective recesses, said second named tumbler adapted to move into locking engagement 55 with its recess when the other tumblers are moved out of locking positions and the bolt is slightly advanced, said bolt having a recess in one face and a spring actuated lug adapted to seat in said facial recess.

4. In a lock, the combination of a locking bolt provided with a plurality of recesses in 60 the side edges thereof, tumblers for locking

engagement in said recesses, keys for rocking said tumblers, one of said tumblers normally lying out of locking engagement with the locking bolt while the remainder are in locking engagement with their respective recesses, said bolt having a recess in one face, and a spring actuated lug adapted to seat in said facial recess and to be unseated by slight outward movement of one of said keys. 70

5. In a lock, the combination of a locking 75 bolt having a series of recesses in the side edges thereof, pivoted tumblers adapted to engage in one recess of each series to lock the bolt, keys for rocking said tumblers and advancing the bolt, said tumblers adapted to 80 successively engage in the recesses of their respective series during the locking or unlocking operation of the lock structure, one side edge of said bolt provided with a second series of recesses, a pivoted U-shaped tumbler adapted to engage in the recesses of the second series at predetermined times during the locking or unlocking operation of the lock. 85

6. In a lock, the combination of a locking 90 bolt having a series of recesses in the side edges thereof, pivoted tumblers adapted to engage in one recess of each series to lock the bolt, keys for rocking said tumblers and advancing the bolt, said tumblers adapted to 95 successively engage in the recesses of their respective series during the locking or unlocking operation of the lock structure, one side edge of said bolt provided with a second series of recesses, a pivoted U-shaped tumbler adapted to engage in the recesses of the second series at predetermined times during the locking or unlocking operation of the lock, said bolt having a recess in one face and a spring actuated lug adapted to seat in 100 105 said facial recess.

7. In a lock, the combination of a locking bolt having a series of recesses in each side thereof, pivoted tumblers adapted to engage in one recess of each series to lock the bolt, 110 keys for rocking said tumblers and advancing the bolt, said tumblers adapted to successively engage in the recesses of their respective series during the locking or unlocking operation of the lock structure, said bolt having a recess in one face, and a spring actuated lug adapted to seat in said facial recess and to be unseated by slight outward movement of said key. 115

8. In a lock, the combination of a locking 120 bolt having a series of recesses in each side edge thereof, pivoted tumblers adapted to engage in one recess of each series to lock the bolt, keys for rocking said tumblers and advancing the bolt, said tumblers adapted to 125 successively engage in the recesses of their respective series during the locking and unlocking operation of the lock structure, said locking bolt provided with a recess in one face, a flat spring, a lug carried by said 130

spring and adapted to seat in said facial recess, said flat spring having a lateral extension formed thereon and adapted to be engaged by one of said keys to unseat the 5 lug upon the slight outward movement of the key.

9. In a lock, the combination of a locking bolt having a series of recesses in each side edge thereof, pivoted tumblers adapted to engage in one recess of each series to lock the bolt, keys for rocking said tumblers and advancing the bolt, said tumblers adapted to successively engage in the recesses of their respective series during the locking and 10 unlocking operation of the lock structure, said locking bolt provided with a recess in one face, a flat spring, a lug carried by said spring and adapted to seat in said facial recess, said flat spring having a lateral 15 extension formed thereon and adapted to be engaged by one of said keys to unseat the lug upon the slight outward movement of the keys, shoulders formed upon said bolt and adapted to be engaged by certain of the 20 keys during rotation and subsequent to the rocking of the tumblers to advance the bolt.

10. In a lock structure, the combination of a locking bolt having a series of recesses in each side edge thereof, pivoted tumblers

adapted to engage in one recess of each series 30 to lock the bolt, keys for rocking said tumblers, said tumblers adapted to successively engage in the recesses of the respective series during the locking or unlocking operation of the lock structure, shoulders formed upon 35 said bolt and adapted to be engaged by certain of the keys during rotation and subsequent to the rocking of the tumblers to advance the bolt.

11. In a lock structure, the combination of 40 a locking bolt having a series of recesses in each side edge thereof, pivoted tumblers adapted to engage in one recess of each series, to lock the bolt, keys for rocking said tumblers, said tumblers adapted to successively engage in the recesses of the respective 45 series during the locking or unlocking operation of the lock structure, shoulders formed upon said bolt and adapted to be engaged by certain of the keys during rotation and subsequent to the rocking of the tumblers to 50 advance the bolt, one side edge of said bolt provided with a second series of recesses, and a pivoted U-shaped tumbler adapted to engage in the recesses of the second series at 55 predetermined times during the locking or unlocking operation of the lock.

THOMAS STEBNER.
